WINDOW CLEANER

Filed Dec. 20, 1929

INVENTOR
C. Stark

BY his
J. Ledermann
ATTORNEY

UNITED STATES PATENT OFFICE

CARL STARK, OF NEW YORK, N. Y.

WINDOW CLEANER

Application filed December 20, 1929. Serial No. 415,377.

The main object of this invention is to provide a window cleaning mechanism which uses a carriage, the latter being lifted and lowered from the window pane and is 5 equipped with such accessories as a rubber pad, squeegee and a brush to which water is fed from a tank forming part of the machine.

Another object of the invention is to provide a window washing machine equipped with a pad, brush and squeegee which may be moved from place to place on a window pane in a quick and convenient manner upon a removable track.

15 The above and other objects will become apparent in the description below in which characters of reference refer to like-named parts in the drawings.

Referring briefly to the drawings, Figure 20 1 is a front elevational view of the device.

Figure 2 is a side elevational view of the device showing the same mounted upon a window sash.

Figure 3 is a top plan view of the cleaner 25 pad.

Referring in detail to the drawings, the numeral 10 indicates the upper beam of a window sash in which the window pane 11 is framed. In the usual construction of windows, locks are provided on the lower window sash which engages an attachment on the upper window sash and therefore any construction that rides upon the lower window frame or sash must be raised above this lock 30 if the mechanism is to pass over the entire width of the window sash. For this reason I propose to use the offset clamps 12 shown in Figure 2, which are temporarily secured to the sides of the window sash in raised position above the lock on the sash through the medium of threaded clamp studs 13. These clamp members 12 are usually two in number and are joined by a longitudinal track 14 upon which rides the entire mechanism of 40 the device. This track is supported in a horizontal plane above the lock and above the sash, and in turn has riding thereon a U shaped frame consisting of parallel sides 15 and 16 upon which sleeves are formed.

50 These sleeves are integral with a frame or

connecting element 18. The frame 18 is provided with ears 19 in which pins 20 are mounted. These pins 20 support grooved rollers 21 which ride upon the track 14 of the device across the area of the window pane 11. The 55 sleeves 17 receive and have secured therein the arms 22 of substantially L shaped rods. From the extremities of these arms 22 vertical extensions 23 project in parallel relation to each other and mutually spaced apart. 60 A bracket 24 connects the arms 22 at the rear of the device. The bracket 24 has a pair of grooved pulleys 27 mounted thereon. The roof 18 of the device is provided with similar grooved pulleys 25 and 26 which latter are 65 aligned with the pulleys 27 on the bracket 24. The extensions 23 of the arms 22 serve as guides for a carriage 28 having mounted on one side a hollow container 29. This container rides with the carriage in a vertical 70 path. The lower extremities of extensions 23 are joined by a connector bar 30. About this connector bar in a grooved portion thereof a cable 31 is trained. One end of this cable is directly connected to a right angle extension 32 of the carriage 28 and trains a quarter turn about one of the pulleys 27 and thence passes about the pulley 26, hanging dependent from this pulley and at its one end is provided with a grip ball 33. This cable when 75 manipulated, after grasping the grip ball 33, lowers the clamp along the entire length of the guide extensions 23. A second cable 34 is secured to the upper end of the carriage 28 and is trained about the other of the pulleys 80 27 and thence trains about the pulley 25 from which it depends and has at its lower extremity a grip ball 35. The device has, as heretofore mentioned, a water container 29 from which a pipe 36 having perforations 85 37 90 therein is positioned directly above the bristles 38 of a brush body 39. This brush body is mounted upon an L shaped bracket and is secured to the carriage member 32. A second member is also secured to this right angle 95 extension 32 and comprises a squeegee frame 40 having a rubber tongue 41 extending therefrom having for its purpose to engage the surface of the window pane when extended. This squeegee frame is adapted to be rotated 100

90° from the operative position shown in Figure 2 to the inoperative position by means of a string 42. A third member is mounted upon the offset extension 32 and comprises a cloth covered pad 43 composed of cork or similar other soft material. The cleaner squeegee and the brush are provided with a tongue 44, having slots 45 therin, which register under the thumb nuts 46 of threaded studs 47, the thumb nuts when manipulated being adapted to secure the tongues of either of these devices in secured position upon the extensions 32 of the carriage. Mounted upon the arm extensions 23 in the lower ends thereof and seated upon the connector element 30 springs 48 are located so that the impact of the descending carriage will be taken up by these springs to prevent any jarring of the device.

20 The device is essentially used to cleanse the outer surface of a window pane, which under ordinary conditions endanger the window cleaner to fall or injury as he places himself in a precarious position upon a window ledge. This device may be conveniently mounted upon the outer surface of the window pane without the operator thereof unnecessarily exposing himself to danger. To permit free travel over the entire surface 30 of the window pane the clamps 12 are first secured to the window sash 10. These clamps locate a track 14 integral with the clamps in raised position over the window sash so that the mechanism will not be obstructed by the 35 latch usually mounted on the sash. The entire device rides upon this track 14 across the width of a window pane. The frame comprising members 15 and 16 and the roof 18 have extending therefrom the extensions 40 23 and arms 22. These extensions 23 guide the carriage 28 in a vertical path as the cable 34 is pulled or taken up. Through manipulation of the grip ball 35 the carriage is raised upon the extensions 23 from the lower 45 end of the latter to the upper. As the carriage arrives at the upper extreme end of the travel the opposing grip ball 33 is manipulated. This takes up on the cable 31 and lowers the carriage as the clamps have either 50 the cleaning pad 43, the squeegee 41 or the brush 38 secured thereto, individually or in combination. These members are adapted to clean the surface of a window pane. The container 29 filled with water delivers this 55 water to a pipe line 36 whose end above the brush bristles is perforated so that the water freely circulates through the bristles of the brush.

60 It is to be noted that certain changes in form and construction may be made without departing from the spirit and scope of the invention.

I claim:

65 In a window cleaner, a frame adapted to be mounted on top of a window sash, a track

mounted upon the window sash, grooved wheels journaled in said frame and rotating on said track over the window sash, said frame being supported on said grooved wheels, vertical extensions projecting downwardly from said frame, a carriage riding on said extensions, detachable means on said carriage for cleaning a window and cable operated means for reciprocatingly actuating said carriage on said extensions.

70 In testimony whereof I affix my signature.
CARL STARK.
